Int. Cl. D7—01

U.S. Cl. D7—23

FIG. 1

FIG. 2

FIG. 3

FIG. 1 is a top perspective view of a dish showing our new design;

FIG. 2 is a bottom perspective view;

FIG. 3 is a side elevational view taken partly in section to illustrate more clearly the concave bottom of the dish.

The design is characterized by the provision of an enlarged concave bottom surface and relatively flat top surface as illustrated in the drawing.

We claim:

The ornamental design for a dish, substantially as shown and described.
